3 Claims. (Cl. 206—65)

This application is a division of my application Serial
No. 271,097, filed April 8, 1963, now abandoned.

The present invention relates to a package of regular and
mutually equal tetrahedrons. Today a great number especially
of liquid products are packed in tetrahedrons and
therefore a demand has been created for suitable transport
packages for a number of such tetrahedrons.

As a transport package it is known to use a hexagonal
container of the type described in the Swedish Patent
175,387. In a container of this type the tetrahedrons
are stacked in a certain pattern so that the container to
an essential degree is filled with tetrahedrons. Through
the tetrahedrons being stacked in the way indicated in
the above patent specification the advantage is gained
that the tetrahedrons get support from the bottom and
side walls of the container as well as from the adjacent
tetrahedrons, wherefore the individual tetrahedrons will
better stand up to any strains occurring and in addition
the stacking permits a high degree of filling of the
container.

One disadvantage with the known containers is, however,
that they are relatively expensive, wherefore they
normally are returned after use. This transport of empty
containers is naturally not desirable from an economic
point of view, and a request has therefore been put forward
for a package for tetrahedrons, where the container is
inexpensive and therefore need not be returned.

The invention indicates a method of obtaining an inexpensive
package for tetrahedrons through making use of
a container of known type as stacking mold when wrapping
a number of tetrahedrons in an inexpensive container.
The method in accordance with the invention is
characterized therein that the container serving as the
stacking mold before putting the tetrahedrons in it, has
been provided with a loose lining of a preferably flexible
material, and that the mentioned lining, when the tetra-
hedrons have been placed therein, is wrapped around the
tetrahedrons to form a package easily removed from the
stacking mold which will keep the tetrahedrons together,
the outer form of said package in the main corresponding
to that of the container serving as a stacking mold.

The invention is in the following described with reference
to the accompanying diagrammatical drawing, in which

FIG. 1 shows a hexagonal container of known type
serving as the packing mold the inside of which has been
provided with a loose lining of a flexible material,

FIG. 2 shows the container and liner filled with tetra-
hedrons and

FIG. 3 shows a package in accordance with the inven-

2

tion being removed from the container serving as the
packing mold during the packing operation.

In FIG. 1 the container described in Swedish Patent
No. 175,387, is provided with a loose lining 2 of a prefer-
ably flexible and elastic film material, for instance poly-
ethylene film. The lining 2 is so large that its outer parts
3 will extend outside the upper edge 4 of the container 1.
After the container 1 has been provided with a lining 2
a bottom layer of six tetrahedrons 7 are placed in it, in
this layer each tetrahedron 7 is resting against the bottom
of the container and also against the side walls 5 of the
container as well as against the adjacent tetrahedrons. A
second layer containing six tetrahedrons 7 are further
placed in such a way that each tetrahedron in this layer
extends in between two tetrahedrons in the bottom layer,
whereby support is obtained from the tetrahedrons in the
bottom layer as well as from the side wall 5 of the con-
tainer 1.

When a suitable number of tetrahedrons have been
placed in the container 1 in the way described above, the
lining 2 is pulled up tightly around the tetrahedron and
the outer parts 3 thereof is folded over the tetrahedrons
7. As it is necessary that the tetrahedrons 7 in the package
should be kept together with sufficient tightness to ensure
that the configuration obtained when stacking in the
container 1 will not get disarranged, the film 2 must be firmly
wrapped around the tetrahedrons to ensure that it tightens
around the outer sides of the tetrahedrons and firmly
presses against them. As the film material described in
the example is elastic, the tightening may be achieved
through collecting and twisting together the outer area 3
of the film, whereafter the film is fixed in the twisted
position.

The finished package 6 shown in FIG. 3 may now be
lifted out of the container 1 serving as a stacking mold
and is ready for distribution.

The example of manufacture shown here has proved
to be advantageous from the point of view of costs as
well as function. Instead of film material it is, however,
possible to use net made from textile fibres or something
similar.

I claim:

1. A package of mutually equal tetrahedrons, said
package comprising a stack of at least two layers with six
tetrahedrons in each layer, said stack being completely
surrounded by and the tetrahedrons being held in their
relative positions by a flexible covering.

2. A package as defined in claim 1 in which the cover-
ing is an elastic film.

3. A package as defined in claim 1 in which the cover-
ing is a net made of textile fibers.
